UNITED STATES PATENT OFFICE.

MIGUEL GONZALEZ, OF NEW YORK, N. Y.

WASHSTAND-TOP.

1,300,378.

Specification of Letters Patent. Patented Apr. 15, 1919.

Application filed June 8, 1918. Serial No. 239,000.

To all whom it may concern:

Be it known that I, MIGUEL GONZALEZ, a citizen of Venezuela, residing in the city, county, and State of New York, have invented certain new and useful Improvements in Washstand-Tops, of which the following is a specification.

My invention relates to a wash stand top which may constitute a complete wash stand coupled to the city water and sewerage system and specifically relates to a ceramic or otherwise molded slab for the top of those forms of wash stands in which the refuse water is collected in a tank confined within 15 a compartment below the top.

The primary object of the invention is to provide a sanitary form of wash-stand top which can be formed readily and cheaply in one-piece and with the least possible complication of mold form to provide the necessary basin, pockets and drainage outlets.

Another object of the invention is to provide in a construction such as is outlined, a set of utensils which can be fitted to the 25 molded form and provided with suitable coverings so as to inclose the soap, brushes, sponges and other articles usually used on wash-stand tops and which can be readily removed for packing and cleaning.

Various other objects and advantages of the invention will be in part obvious from 30 an inspection of the accompanying drawings and in part will be more fully set forth in the following particular description of 35 one form of mechanism embodying my invention, and the invention also consists in certain new and novel features of construction and combination of parts hereinafter set forth and claimed.

Referring to the accompanying drawings:—

Figure 1 is a plan view looking down upon a wash-stand top constituting a preferred embodiment of my invention;

Fig. 2 is a plan view of the underside of the device shown in Fig. 1;

Fig. 3 is a transverse vertical sectional view taken from front to rear on the line 3—3 of Fig. 1; and

Fig. 4 is a detailed vertical sectional view taken on either of the lines 4—4 of Fig. 1.

In the following description and in the claims, parts will be identified by specific means for convenience of expression but 55 they are intended to be as generic in their

application to similar parts as the art will permit.

The device selected for illustration is shown in the form of a slab having a flat top 10 with an upstanding outlining rim 11, 60 as is usual in such constructions. The slab is provided centrally thereof adjacent the front edge 12 with a relatively large semi-ellipsoidal depression 13 constituting a wash-bowl. The wash-bowl is provided adjacent its lowest point with a drain outlet opening 14 for discharging the contents of the bowl into the receptacle in the bottom of the wash-stand but it is obvious that the outlet may be connected with the usual 65 sewer pipe system. A hollow protuberance 15 is formed at the back-side of the slab and positioned in the angle formed between the bowl and the rearwardly projecting portion of the top 10 as shown particularly in Fig. 75 3. The protuberance 15 is formed hollow and has its lower portion defined by a drip outlet nozzle 16 depending therefrom and designed to lead the drip water into the receptacle in the bottom of the wash stand or 80 is connected to the sewer system as previously suggested.

The bowl is provided with a tube 17 depending downwardly and rearwardly from the upper portion of the bowl and leading 85 through the hollow protuberance 15. The side of the bowl just below the entrance of the tube 17 thereto is provided with a supplemental outlet port 18 opening into the interior of the protuberance 15 and designed 90 to convey overflowing water from the bowl through the nozzle 16. The bowl end of the port 18 and tube 17 are positioned beneath an overhanging apron 19. The tube 17 may be utilized, in one form of the invention, as 95 a supply pipe for the purpose of admitting water to the basin, in which case the vent 18 will constitute the discharge port from the basin but it is obvious that both the tube 17 and the nozzle 16 may both constitute discharge conduits.

The portion of the slab above the protuberance 15 is depressed to form a tooth brush pocket 20, elongated as shown in Fig. 1 and of a size to contain one or more tooth 105 brushes. The portion of the slab outlining the upper edge of the depression 20 is recessed to provide an out-lining seat 21 upon which seat is fitted a cover 22. The cover is perforated as shown at 23 in Fig. 1, so as to 110

provide ventilation through the pocket. The bottom of the depression 20 is provided with drain openings 24 so that water may drip from the pocket into the protuberance 5 and therefrom discharged through the outlet nozzle 16.

The back portion of the top and on opposite sides of the tooth brush pocket, is recessed to provide semi-spherical depressions, 10 25 and 26, forming pockets for containing brushes, sponges, soaps, or other articles usually found on wash-stands. As these depressions are similar in construction a detailed description of either one will be sufficient for the other.

The bottom of the recess is provided with drain openings 27 as shown in Fig. 4 and lead therefrom into a conduit 28 formed integral with the slab. The conduit leads from 20 the bottom of the pocket into the wash-bowl adjacent the bottom thereof. The pocket is provided with a demountable utensil which includes a disk 29, having a configuration designed to fit snugly within the pocket so 25 as not to be knocked therefrom accidentally but having such a fit that it can be readily removed for cleaning, repairing and the like. The bottom of the dish is provided with outlet vents 30 so that water will be 30 discharged therefrom through the vents 27 and conduit 28 into the bowl. The portion of the top outlining the pocket is provided with an annular recess 31 in which is fitted a cover 32 for closing the top of the dish. 35 By means of a device of this character it is possible to provide a neatly formed wash-stand top of a form which will lend itself readily to the molding process used in forming tops of ceramic material. The device 40 is designed to employ the least possible amount of material consistent with the rigidity desired in a device of this character and the parts are disposed so as to take advantage of the mutual bracing provided by 45 the necessary structural parts.

As all of the depressions are formed of wide open pockets the cleaning of the same is facilitated and the removable feature of the utensils permits these parts to be readily 50 removed from the slab and cleaned by boiling or other approved processes. The countersunk cover-receiving seats provide for a securing of the covers in position against

accidental displacement and the curved dome shaped top of these covers permit 55 water or other matter falling thereon to slide off into the basin from which they are discharged through the drain outlet opening 14.

Having thus described my invention, I 60 claim:

1. In a device of the class described, the combination of a one piece molded slab for a wash stand including a substantially flat top provided with a relatively deep depression 65 designed to constitute a wash basin, said slab provided with an outlet therefrom extending through the depression to drain the liquid therefrom, a hollow protuberance positioned between the basin and the flat 70 top, the portion of the top above said protuberance being recessed to form a relatively deep dish shaped depression provided with a drain opening for discharging into said protuberance, a relatively deep dish 75 designed to fit snugly within said dish shaped depression and provided with vents for draining therefrom through said drain opening, the portion of the slab outlining the upper edge of said dish shaped depression 80 being recessed slightly below the top of the slab to provide a cover seat above the upper edge of the seated dish and a cover for the dish fitted to said seat.

2. In a device of the class described, the 85 combination of a one piece molded slab for a wash stand including a substantially flat top provided with a relatively deep depression 90 designed to constitute a wash basin, a hollow protuberance positioned between the basin and the flat top, the portion of the top above 95 said protuberance being recessed to form a relatively deep dish shaped depression, a relatively deep dish designed to fit snugly within said dish shaped depression, the portion of the slab outlining the upper edge of said dish shaped depression being recessed slightly below the top of the slab to provide a cover seat above the upper edge of the seated dish and a cover for the dish fitted to 100 said seat.

Signed at New York city, in the county of New York and State of New York this 28th day of May, A. D. 1918.

MIGUEL GONZALEZ.
